UNITED STATES PATENT OFFICE.

MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS.

Application filed December 8, 1921. Serial No. 520,836.

To all whom it may concern:

Be it known that I, MALCOLM L. COSSITT, a citizen of the United States, residing at Alameda, in the county of Alameda and 5 State of California, have invented certain new and useful Improvements in Manifolding Attachments for Typewriters, of which the following is a specification.

My invention relates to that class of mani- 10 folding attachments for typewriters and like type-impact machines, in which a manifolding member carried by a pair of spaced arms movably mounted upon the platen-carriage of the machine is adapted to be placed in and 15 removed from a functional position between the sheets of paper, in the line of type-impact.

My present invention has for its main ob- 20 ject the use of a relatively extensive sheet or strip of manifolding material associated with the attachment and stored in small compass in a manner adapting it to be drawn out to expose for use a limited transverse section, said section being torn or cut off when 25 exhausted, and a fresh section drawn out and brought into use.

The manifolding sheet or strip may be of any suitable material, though in its most practicable form it is what is known as 30 "carbon paper", as such paper lends itself both for efficiency and economy, to the best results.

The nature of my invention, in several 35 forms and modifications will be clearly ascertained from the following description, as illustrated by the accompanying drawings; though it is to be understood that changes in these forms may be made within the scope of the appended claims, without departing 40 from the spirit of the invention.

In the drawings:—

Fig. 1 is a front elevation of my manifolding attachment, showing one of the manifolding-member carriers moved down, and a 45 section of the manifolding member drawn out to position in front of the platen of the typewriter, the other carriers being in elevated position, out of use.

Fig. 2 is an end view of the same, the dot-

ted lines showing the movement of said carriers.

Fig. 3 is a top-plan, broken, of my attachment.

Fig. 4 is a sectional detail showing one of the carriers in position with relation to the 55 platen, and the manifolding-member drawn out from its casing to present a section for use in the line of type-impact.

Fig. 5 is a detail section showing a simple means for releasably locking the carriers in 60 position.

Fig. 6 is an end view showing the casings for the manifolding-members, mounted on the carrying arms in a position adapting the manifolding sheets to be drawn up to func- 65 tional position, instead of down, as in preceding figures.

Fig. 7 is an enlarged sectional detail of the arrangement of Fig. 6.

Fig. 8 is an end view, showing the storing 70 of the manifolding members in rolls on the carrying arms.

Fig. 9 is an enlarged sectional detail of the arrangement of Fig. 8.

I have herein shown as one form of a 75 manifolding-attachment, a pair of standards 1 adapted for connection with the carriage 9' of the platen 9 of a typewriter. Between the standards are mounted a plurality of nested sleeves 2, each independently ro- 80 tatable and each carrying a pair of arms 3, which are adapted for arcuate movement.

Extending between and carried by each pair of arms is a chambered member which in one form is a casing 4 having an opening 85 5 in its front fitted with a guide roll 6. Fig. 4. Within the casing 4 is stored, in fan-fold shape, Fig. 4, the manifolding member 7, which, as above stated, is preferably a rel- 90 atively long sheet or strip of carbon-paper, adapted to be drawn out through the opening 5. Between the extremities of the pair of arms is a slotted rod 8 through which the carbon paper is drawn, Fig. 4. When out of use the arms are thrown up out of the 95 way. But when a single carbon copy is required, one pair of arms are thrown down to a position shown in Figs. 1 and 4, and, the

carbon paper 7, being drawn out from the casing 4 and passed through the slitted rod 8, as in Fig. 4, presents a relatively narrow transverse section 7' in the line of type-impact.

When this section 7' of carbon paper is used up, it is torn off against the rod 8, and a fresh section is drawn out for use, and this continues until the store of carbon paper 10 within the casing is exhausted, whereupon a fresh store is supplied, the casing being formed with a cover 4' to permit access to its interior. Fig. 4.

If plural copies are to be made, plural arms 15 are moved down to functional position, as indicated by the dotted lines in Fig. 2.

In Figs. 6 and 7, wherein similar numerals indicate similar parts, a modification is shown in which the carrying arms 3 are 20 somewhat lengthened, so that the casings 4 may be reversed with respect to their delivery sides, and may be carried far enough below the line of type impact to adapt the carbon paper to be drawn up, instead of 25 down, into functional position, as clearly shown in Fig. 7.

In Figs. 8 and 9 a form is shown in which the carbon-paper instead of being housed within a casing, is carried by a member in 30 the form of a reel or roll 10, mounted on the arms. The roll 10 may be above or below the line of type impact, though for illustration I have shown it above, and the carbon paper passing down through two slitted 35 rods 8.

In Fig. 5, I show a simple means for releasably locking the carrying arms, consisting of the spring-pressed balls 11 coacting with said arms.

40 I claim:—

1. A manifolding attachment for typewriters comprising a carrying member; means for mounting said member on the platen carriage of the machine, adapting it 45 for movement towards and away from the line of type-impact; a chambered member mounted upon said carrying member; and a manifolding sheet within said chambered member and adapted to be drawn therefrom to present successive sections in the line of type-impact.

2. A manifolding attachment for typewriters comprising a pair of spaced arms; means for mounting said arms upon the 55 platen-carriage of the machine adapting them for movement towards and away from the line of type-impact; a carrying member secured to said arms; and a manifolding sheet carried by said member and adapted 60 to be drawn therefrom to present successive sections in the line of type impact.

3. A manifolding attachment for typewriters comprising a pair of spaced arms; means for mounting said arms upon the 65 platen-carriage of the machine adapting

them for movement towards and away from the line of type-impact; a carrying member secured to said arms; a manifolding sheet carried by said member and adapted to be drawn therefrom to present successive sections in the line of type impact; and means carried by said arms for holding the free end of the drawn out section. 70

4. A manifolding attachment for typewriters comprising a pair of spaced arms; 75 means for mounting said arms upon the platen-carriage of the machine adapting them for movement towards and away from the line of type-impact; a carrying member secured to said arms; a manifolding sheet 80 carried by said member and adapted to be drawn therefrom to present successive sections in the line of type impact; and a slitted rod carried by said arms, through which the free end of the drawn out section 85 is passed and against which said section is torn off.

5. A manifolding attachment for typewriters comprising an apertured casing; means for mounting said casing on the platen carriage of the machine; and a manifolding sheet fan-folded within said casing and adapted to be drawn therefrom to 90 present successive sections in the line of type impact. 95

6. A manifolding attachment for typewriters comprising an apertured casing; means for mounting said casing on the platen carriage of the machine, adapting it 100 for movement towards and away from the line of type-impact; and a manifolding sheet fan-folded within said casing and adapted to be drawn therefrom to present successive sections in the line of type impact.

7. A manifolding attachment for typewriters comprising a pair of spaced arms; means for mounting said arms upon the platen carriage of the machine adapting them for movement towards and away from the line of type-impact; an apertured casing 110 carried by said arms; and a manifolding sheet fan-folded within said casing and adapted to be drawn therefrom to present successive sections in the line of type-impact. 115

8. A manifolding attachment for typewriters comprising a pair of spaced arms; means for mounting said arms upon the platen carriage of the machine adapting them for movement towards and away from the line of type impact; an apertured 120 casing carried by said arms; a manifolding sheet fan-folded within said casing and adapted to be drawn therefrom to present successive sections in the line of type-impact; and means carried by said arms for holding the free end of the drawn out section. 125

9. A manifolding attachment for typewriters comprising a pair of spaced arms; 130

means for mounting said arms upon the platen carriage of the machine adapting them for movement towards and away from the line of type impact; an apertured casing carried by said arms; a manifolding sheet fan-folded within said casing and adapted to be drawn therefrom to present successive sections in the line of type-

impact; and a slotted rod carried by said arms, through which the free end of the ¹⁰ drawn out section is passed and against which said section is torn off.

In testimony whereof I have signed my name to this specification.

MALCOLM L. COSSITT.
